CLAIM

The ornamental design for a chair, as shown and described.

DESCRIPTION

FIG. 1 is a front view of the chair of my design;
FIG. 2 is a top view of the chair;
FIG. 3 is a rear view of the chair; and,
FIG. 4 is a left side view of the chair (the right side view of
the chair is a mirror image of this view and is not shown).
The bottom of the design is flat and unornamented.
